UNITED STATES PATENT OFFICE

163,222

MATERNITY SLIP OR SIMILAR ARTICLE

Hermine Rees, Arlington, Mass.

Application June 21, 1949, Serial No. 3,432

Term of patent 14 years

(Cl. D3—26)

To all whom it may concern:

Be it known that I, Hermine Rees, a citizen of the United States, residing at 105 Mystic Street, Arlington, in the county of Middlesex and Commonwealth of Massachusetts, have invented a new, original, and ornamental Design for a Maternity Slip or Similar Article, of which the following is a specification, reference being had to the accompanying drawing forming part thereof.

In the drawing:

Figure 4 is a back view of the maternity slip or similar article; and

I claim:

The ornamental design for a maternity slip or similar article, substantially as shown.

HERMINE REES.
